UNITED STATES PATENT OFFICE.

FRANCIS D. PROCTOR AND ALDO LOSSON, OF MONROE CITY, MISSOURI.

AUTOMATIC SAFETY-GATE.

1,331,673.

Specification of Letters Patent. Patented Feb. 24, 1920.

Application filed August 27, 1919. Serial No. 320,239.

To all whom it may concern:

Be it known that we, FRANCIS D. PROCTOR and ALDO LOSSON, citizens of the United States, residing at Monroe City, in the county of Monroe, State of Missouri, have invented a new and useful Automatic Safety-Gate, of which the following is a specification.

This invention relates to improvements in automatic gates, and more particularly to railway gates employed for guarding railway crossings against persons crossing the same, when a train is approaching the highway.

15 The primary object of the invention is to provide a gate of this character which will be operated by a train passing over the track, the train engaging suitable operating levers located within the path of travel of the train.

20 A further object of the invention is to provide means for opening the gate, after the train has passed the high-way intersecting the railway tracks, thereby obviating the necessity of employing an attendant at the crossing for operating the gate.

25 A still further object of the invention is to provide means having connection with the operating levers, for causing a gradual raising and lowering of the gate proper.

30 With the foregoing and other objects in view which will appear as the description proceeds, the invention resides in the combination and arrangement of parts and in the 35 details of construction hereinafter described and claimed; it being understood that changes in the precise embodiment of the invention herein disclosed, may be made within the scope of what is claimed without departing from the spirit of the invention.

40 Referring to the drawing:—

Figure 1 illustrates a side elevational view of a gate, showing the support or housing thereof, in section, the gate being shown in 45 its raised position by dot and dash line.

45 Fig. 2 is a fragmental top plan view of the same, and

Fig. 3 illustrates a side elevational view showing a fragment of a railway track, with 50 our invention applied thereto.

Having reference to the drawing in detail, the reference character 5 designates the base of the housing or support, which includes the side elements 6 and 7 and end members 55 8 and 9, the side members 6 being provided

with a cut-out portion 10 extending from the upper edge thereof, and terminating at a point intermediate its length, said cut-out portion being for the purpose of providing 60 a guide for one end of the gate 11.

The side element 7 provides a support for the bracket 12, which has one of its arms secured to the inner wall thereof, as at 13, the outer arm of said bracket 12, providing a pivot for the dog 14, which has its lower end 65 connected to the coiled spring 15, said coiled spring 15, having connection with the side element 7, thereby forcing the outer end of said dog 14 normally into engagement with the sprocket wheel 16 which is rotatably supported within the housing, on the shaft 17.

70 This sprocket 16, is provided with a cut-out portion 18, in the periphery thereof, which cut-out portion forms an abutment for the dog 14, when the sprocket wheel 16 75 has been moved to a predetermined position, and it will be seen that due to the engagement between the dog 14 and notched portion 18, the sprocket wheel 16 is prevented from reverse movement, under normal conditions. 80

The gate proper which includes the arm 11, is pivotally connected as at 19, to the upper portion of the housing, and is provided with the weight 20, adjustably secured to the 85 extreme inner end of the gate, as by means of the screw shank 21, operating in a suitable threaded opening 22 formed in the inner end of the arm 11.

Keyed or otherwise secured to the shaft 90 19, is the arm 23, which includes the sections 24 and 25, said sections 24 and 25 being under the tension of the coiled spring 26, which has its respective ends connected to the respective sections 24 and 25 by means of 95 the bracket members 27 and 28.

On one end of the section 25, is adjustably secured a weight 29, which weight is also provided with a threaded supporting shank operating in an opening 31, formed in the 100 section 25, to permit the weight to be moved with relation to the section 25 to a position to overbalance the weight 20 on the inner end of the arm 11, in order that the gate will operate to close, when the means for supporting the gate in its open position has been released.

The section 25, of the arm 23, normally rests on the bracket 32, which extends laterally from the arm 11, in such relation 110

with the section 25, that the section 25, will engage said arm 32 and be supported thereby.

The operating mechanism includes the 5 yoke 33 having an extension 34, and the forked portion 35, one of the said forked portions being pivotally connected to one of the arms of the bell crank lever 36, the opposite end of said arm having connection 10 with the flexible member 37, which passes over the pulley 38 supported on the bracket 39, which is suitably secured to a railway tie, in close proximity with the rail, supported thereby, so that the operating lever 15 40, which is pivotally connected to the bracket 38, will lie in the path of travel of an arm, not shown, carried by the train passing over the track.

As shown, the flexible member 37 passes 20 over the pulley 41, which is supported by the bracket 42, from where it passes to the pulley 43 supported within the housing or support, the extreme end thereof having connection with the sprocket chain 44, operating over the sprocket wheel 16, the sprocket chain 44 having connection with the section 24 of the arm 23, through the medium of the flexible member 45.

The extension 34, which forms a part of 30 the yoke 33, has connection with one end of the dog 14, through the flexible member 46, which passes through an opening 47, formed in the side element 7 of the housing.

While we have only shown and described 35 the connection between the yoke 33 and the operating lever 40, on one side of the gate, it is of course understood that the same is duplicated on the other side of the gate, therefore it is not believed to be necessary 40 to dwell in detail on this construction.

Assuming that the gate is in its opened 50 position:

From the foregoing, it will be seen that if a train were passing over the rails in the 55 direction of the arrow A, as indicated by Fig. 3 of the drawings, the lever 40 would be tripped, with the result that the bell crank lever 36 would be rocked to pull the flexible connection 46, with the result that the dog 14 would be released from the cut-out portion 18 of the sprocket wheel 16, the weight 29, being slightly heavier than the weight 20, the gate 11 would descend, or move to its closed position.

It follows that as the train proceeds, the 60 operating lever, on the other side of the gate, and corresponding to the operating lever 40, is moved in a direction corresponding with the movement of the operating lever 40, with the result that the flexible connecting member 37, is pulled, with the result that the sprocket chain 44 is moved downwardly over the teeth of the sprocket wheel 16, until the dog 14 reaches the cut-

out portion 18, whereupon the tension of the 65 coiled spring 15, causes the dog 14 to seat in the cut-out portion 18, thereby preventing reverse rotary movement of the sprocket wheel 16, and consequently supporting the gate 11 in its open position. 70

What is claimed is:—

1. In an automatic railway gate, a pivoted arm, a housing for supporting the arm, a sectional arm connected to the pivoted arm, spring means for connecting the sections of 75 the sectional arm, a weight carried by one of the sections, a weight carried by one end of the pivoted arm, the weight on the sectional arm being heavier than the weight 80 on the pivoted arm, and means for overcoming the weight of the sectional arm.

2. In an automatic railway gate, a pivoted arm, a housing, a sectional arm supported by the pivoted arm, said sectional arm having a weight, and a weight on one 85 end of the pivoted arm, a sprocket wheel within the housing, an operating lever, a flexible member connecting the sectional arm and the operating lever, said flexible member operating over the sprocket wheel, 90 for moving the pivoted arm and sectional arm in one direction, and means for securing the sprocket wheel against movement in one direction, at predetermined positions.

3. In an automatic railway gate, a housing, 95 an arm pivotally connected to the housing, an auxiliary arm operating with the first mentioned arm, a weight carried by the first mentioned arm, and a weight on the auxiliary arm, the weight on the auxiliary arm adapted to overbalance the weight 100 on the first mentioned arm, and means for overcoming the weight of the auxiliary arm, to move the first mentioned arm to its open position. 105

4. In an automatic railway gate, a pivoted arm, a housing for supporting the arm, a sectional arm supported adjacent the pivoted arm, a bracket supported by the pivoted arm, and adapted to receive one of the 110 sections of the sectional arm, a weight carried by the sectional arm and a weight carried by the pivoted arm, the weight of the sectional arm adapted to overbalance the weight of the pivoted arm, means for automatically removing the weight of the sectional arm from the pivoted arm, and means for returning the sectional arm to its position on the bracket. 115

In testimony that we claim the foregoing 120 as our own, we have hereto affixed our signatures in the presence of two witnesses:

FRANCIS D. PROCTOR.
ALDO LOSSON.
